SYSTEM OF SUBMARINE SOUNDING

Raymond Villem, Paris, France, assignor to Societe Francaise Radio Electrique, a corporation of France

Application November 27, 1945, Serial No. 631,059
In France January 20, 1943

Section 1, Public Law 690, August 8, 1946
Patent expires January 20, 1963

1 Claim. (Cl. 116—27)

1 This invention is for improvements in or relating to a system of submarine sounding on board vessels. As a result of experience, it has been found that according to the condition of the sea the regularity of the indications supplied by the sounding equipment installed on board vessels is improved if the projector is arranged in a recess formed in the hull of the vessel.

By the term "projector" there is meant either a horn destined for transmission or a device destined for reception. In the latter case, the influence of the condition of the sea upon the working of the sounding system is particularly noticeable.

Such an arrangement, however, necessitates cutting away a portion of the hull of the vessel and consequently adds materially to the difficulties of installation.

The object of the present invention is the elimination of the necessity of cutting away a portion of the hull of a vessel whilst preserving the regularity of the indications.

The invention consists essentially in mounting on the outside of the hull of a vessel a deflector which consists essentially in principle of ensuring that the part of the installation which transmits the vibrations to the water or receives the vibrations from the liquid medium, is out of the zone of air bubbles produced along the hull by the displacement thereof.

The invention will be more particularly described with reference to the accompanying drawing which illustrates in sectional elevation one method of carrying out the invention.

On the hull 1 of the vessel there is directly secured as by welding, as is well known, a watertight container 2, closed by a cover 3, attached by bolts 4, the tightness being assured by the joint 5. A projector 6 is secured in the interior of said container, which is carefully filled with water, to the cover 3, by the bolts 7 effecting the tight joint 8. The projector 6 is shown here by way of example as being of the Fessenden type, which is described on page 249 in "Acoustics" by Stewart and Lindsay, D. Van Nostrand Co. publishers, New York, 1930; but any acoustic or ultra-acoustic projector using magnetostriction or quartz is also suitable. The beam emitted by the vibrating plate 9 has, by way of example, an angular opening or spread as shown at 10. The deflector arrangement which is the subject of the present invention comprises a truncated cone of sheet metal 11 and the central cylinder 12 also of sheet metal. The deflector is secured by its large base to the hull by welding, for example, opposite the

5 container 2, in such a manner that the axis of the cylinder 12 substantially coincides with the axis of beam 10. The deflector 11—12 being very rigidly attached to the hull 1 vibrates with it, and the beam 10 can well be larger than the cylinder 12 without harm to the functioning of the apparatus. A small tube 13, opening at one end at 14 into the cylinder and at the other end to free air above the water level, advantageously 10 serves to draw out the air bubbles which may accidentally occur in the cylinder 12.

15 The same arrangement is applicable to reception, the microphone replacing the projector 6 and being mounted so that the axis of its receiving diaphragm coincides with the axis of the cylinder 12.

Under the above conditions it is found that the weakening, if any, due to the passage of the vibrations through the hull is only slight and 20 the transmission or reception can be carried out in practice as efficiently as when the projector is attached to the hull so as to be in direct communication with the outside water.

Otherwise, from the point of view of protecting 25 the arrangement against the weakening of signals and parasite noises caused by bubbles of air, conditions are found to be similar to those of a projector mounted in a recess formed in the hull.

30 What I claim is:

A system of submarine sounding on board vessels comprising a container filled with water, mounted within the hull of the vessel, a sound projector located within the said container, a deflector having substantially the shape of a truncated cone provided with an open central cylinder, whose axis is substantially the axis of the said cone and mounted with the base secured to the hull, outside of the latter, the axis of the deflector being substantially the axis of the acoustic beam of the said projector.
